L. W. SERRELL.
VACUUM PRODUCING APPARATUS.
APPLICATION FILED JUNE 23, 1909.

965,025.

Patented July 19, 1910.

UNITED STATES PATENT OFFICE.

LEMUEL WILLIAM SERRELL, OF PLAINFIELD, NEW JERSEY, ASSIGNEE TO THE VACUNA COMPANY, OF EAST ORANGE, NEW JERSEY, A CORPORATION OF NEW JERSEY.

VACUUM-PRODUCING APPARATUS.

965,025.

Specification of Letters Patent. Patented July 19, 1910.

Application filed June 23, 1909. Serial No. 503,803.

To all whom it may concern:

Be it known that I, LEMUEL WILLIAM SERRELL, a citizen of the United States, residing at Plainfield, in the county of Union and State of New Jersey, have invented an Improvement in Vacuum-Producing Apparatus, of which the following is a specification.

The device of my present invention is designed as an improvement upon the device shown and described in my application for Letters Patent filed August 1, 1908, Serial No. 446,370 with the object of increasing the efficiency, reliability and output of the device and providing relatively larger areas for expansion of the air between the revoluble devices of the series.

In the device of my present invention, the revoluble devices are in series spaced a predetermined distance and mounted upon a central shaft in suitable bearings and driven by a motor common to all. Each revoluble device or impeller consists of an imperforate disk mounted upon a flanged hub upon the shaft with the blades of the impellers extending between said disk and an over-head plate ring substantially agreeing in width with the series width of the impeller blades; the periphery of each plate ring is curved outward and downward as a delivery wall to the plane of the disk. The inclosing case is of gradually increasing diameters from the inlet to the exit and the same is off-set in cross section to conform closely to the periphery of the revoluble devices. The case is provided with spaced partition rings or separators secured thereto extending inwardly therefrom and placed directly over the revoluble impeller devices and there are air expansion chambers between the impellers. The inner edges of these rings are preferably turned down slightly into the central portion of the revoluble devices and close off any gap between the same and the overhead plates of the revoluble devices so as to insure the delivery of the air from each chamber intervening between the revoluble devices equally into the space produced in the revoluble devices between the inner edges of the impellers. The openings in these rings are also of increasing diameters corresponding relatively with the other parts.

In the drawing, Figure 1 is a vertical section and partial elevation representing the

devices of my improvement. Fig. 2 is a sectional plan through a portion of one of the revoluble devices and Fig. 3 in enlarged size is a section through the edge or periphery of one of the revoluble devices. 60

I provide a central shaft *a* upon which at spaced intervals are mounted flanged hubs, the said hubs being pinned or keyed to the shaft in any desired manner. This shaft is mounted in a suitable ball-bearing *b* at its 65 lower end and in another suitable ball-bearing *c* at its upper end. The character of these ball-bearings however is not material as any suitable bearing allowing a high speed of rotation may be employed to advantage. 70

I have shown an electric motor *d* with brushes bearing upon the commutator at *d*¹ as adapted to provide the power necessary for rotating the central shaft. The character of this motor and its commutators are not material as they may be of any known or suitable type. The electric motor *d*, its commutator *d*¹ and the lower ball-bearing *b* are mounted in any desired or suitable manner in a supporting base *e* of annulus type, which in turn is adapted to carry the case or shell of the vacuum producing apparatus, at the upper end of which is supported the upper ball-bearing *c* and upon the top of 85 which case or shell it is preferable to place and mount a suitable dust-collecting device. This supporting base or frame *e* is preferably of annulus type providing a flange at its upper end to receive the lower edge of the 90 case or shell for the vacuum producing apparatus.

Each revoluble device in series comprises an imperforate disk *f* of suitable metal, at its center surrounding the hub *a*¹ and riveted 95 to the flange thereof. These parts may also be soldered together if desired so as to make the same air-tight.

h represents the blades of the impellers which extend to a point adjacent to the periphery. These are of slightly curved form and are placed at such an inclination that they cross radial lines from the center of the shaft *a*. These blades are shown as each provided with lugs 2 adjacent to their lower 105 edges, which are preferably riveted to the disk *f*, and I provide an overhead plate ring *i* adapted to rest on the upper edges of the blades to the inner edge of the ring, coinciding with the inner ends of the impeller 110

- blades and at the outer edge of the ring extending beyond the outer ends of the blades and outer edge of the imperforate disk f and with its outer periphery i^1 curved 5 outward and downward to substantially form a quarter circle so as to produce a curved delivery wall. This plate ring i and the disk f are preferably permanently and rigidly connected together by rivets 3 shown 10 especially in Figs. 2 and 3, which are set at intervals and whose shouldered ends are securely overturned against the upper surface of the plate ring i and the under surface of the disk f .
- 15 I do not limit my invention to forming the blades as separate pieces and securing them respectively to the disk f and ring i . It will be noticed from Fig. 1 that there are sections shown of the impeller blades h .
- 20 These only represent the radial bi-secting lines of the section which cut through the curved impeller blades at one place or another. The construction described of the impeller blades forms between the disk f , 25 plate ring e and the curved impeller blades h numerous throats or passage-ways through which the air is drawn from above and from the inner space within the inner ends of the blades between the same with the rotation 30 of the impeller devices, the air impinging in transit against the curved edge i^1 of the over-head plate ring i and being deflected downward into the air expansion chamber below the revoluble device. This 35 is the case with each revoluble device, and it will be noticed particularly from Fig. 1 that the uppermost revoluble device is the smallest in diameter, that the lowest is the greatest in diameter and that 40 the second device is intermediate of the two. Correspondingly that as the impeller blades increase in length proportionately to the diameter of the revoluble impeller device the over-head plate rings also increase in 45 proportion to the diameter, and furthermore that the openings between the inner ends of the blades in the several revoluble impeller devices also increase in diameter in proportion.
- 50 The case or shell k is preferably an integral member also of increasing diameter from the upper or inlet to the lower or exit portions. The said case or shell is provided with off-sets or shoulders k^1 of curved form 55 substantially agreeing with the curved edges or peripheries of the revoluble devices and the lower edge of the case or shell rests upon and is secured to the upper annulus edge of the supporting base or frame.
- 60 I provide partition rings or separators l and secure the outer edges thereof to the inner surface of the case or shell at the flat surfaces produced just above the off-sets or shoulders k^1 by screws 5 or other suitable 65 means. These partition rings come over or

above and lie parallel with the overhead plate rings of the revoluble devices so that there is between the two a slight space, enough for ample clearance as between a stationary and moving part. The spaces produced in the case between the under surfaces of the revoluble impeller devices and the rings or separators l constitute air expansion chambers. The inner edges of these partition rings or separators are over-turned 70 as shown at 4 ; the over-turned portion extending down into the open center of the revoluble devices within the inner ends of the blades and below the plane of the plate rings i so as to close off the gap between said plate rings and the partition rings, and direct the air down into the open center of the revoluble devices to pass below the lower edge of the over-turned part 4 and into the throats hereinbefore referred to. 75

80 The top k^2 of the case or shell has its inner edge turned down or over-turned to correspond with the over-turned inner edge 4 ; said top k^2 performing the function of the partition rings l and acting above the 85 uppermost revoluble device as the equivalent of a partition ring and also as a support for any suitable vessel receiving the dust from the dust laden air as the same may be drawn into and through the device.

90 In the operation of the device the air is drawn into the vacuum producing apparatus through openings in the case supporting the upper ball-bearing c and within the central opening produced between the inner edges of the top k^2 of the case; the air passing through the throats of the uppermost revoluble device and being delivered into the expansion chamber of the case produced between the upper revoluble device 95 and the next lower device, where the air has a chance to expand into the increasing diameter of the case. The second or next lower revoluble device of increasing diameter is also of increasing operative capacity 100 in excess of the uppermost revoluble device and it will therefore take more air. The air in the upper chamber is deflected by the upper partition ring l over the inner edge 4 105 into the throats of the revoluble device and passing through the same is turned down by the over-turned edge i^1 into the second chamber where because of the increasing diameter of the case, the air there may expand. The air from this chamber is delivered into the throats of the lowermost revoluble device which because of its greater diameter will take more air than the revoluble device above, and the air passing through the throats of the lower revoluble device is 110 deflected downward from the upper curved edge i^1 into the lowermost and larger chamber, and at this place I have shown and prefer to provide a curved annulus or case m secured at its upper edge to the case or 115

120

130

shell *k* and having an open center around the electric motor and through which the volume of air as delivered escapes into the atmosphere and simultaneously acts to keep the motor cool.

The structure shown in Fig. 1 is advantageously mounted so as to be easily moved about when required, upon casters or rollers *o*, one of which I have shown on the left hand of Fig. 1. This enables the machine to be moved by hand over the surface of the floor or covering, but as the same forms no part of my invention, the structure upon which the machine is mounted is not of material importance.

I have hereinbefore described that the inner edges 4 of the partition rings *l* close off the gap between the plate rings *i* and partition rings *l* so as to direct the air into the throats of the impeller blades, and that the air from the throats is diverted or turned down by the over-turned edges *i'*. This construction and operation effects a seal of the air between the chambers in the case, between the outer surfaces of the edges *i'* and inner corresponding surfaces of the shoulders *k'* preventing any return action of the air, and in fact creating a suction action like an ejector to pull a small percentage of the air through in the same direction. The vacuum is thus maintained unbroken in the chamber above each impeller without any mechanical or frictional seal.

I have herein shown and described the impeller blades *h* as curved and crossing radial lines because the same represents the best and most successful form thereof, but I do not herein limit my invention thereto as the impeller blades might be straight and placed on radial lines, nor do I limit my invention to the character of the blades, and while I have shown the apparatus as set vertically it may be set with the shaft horizontal and I do not therefore limit my invention in this particular.

In the drawing I have shown the case of tapering parts of gradually increasing diameters, but I do not limit myself to this precise form as the parts of gradually increasing diameters may be parallel sided instead of tapering.

I claim as my invention:

1. A vacuum producing apparatus comprising spaced impellers of gradually increasing diameters, each having an inclined periphery bent in the thickness of the impeller to a deflecting delivery edge, a case also of gradually increasing diameters extending around the impellers and having off-set portions which agree in sectional contour with the peripheries of the impellers and in which are expansion chambers between the impellers, and a suction inlet at the smaller part of the case through which air is drawn into the case and expands to-

ward and is delivered from the larger end of the case.

2. A vacuum producing apparatus comprising revoluble devices of gradually increasing diameter, each device consisting of an imperforate disk suitably mounted, impeller plates secured to the upper surface thereof within the periphery and placed across radial lines, an over-head plate ring coming against the top edges of the impellers with means for securing the plate member and the said disk in a permanent relation, and the over-head plate ring having a downwardly curved edge extending out beyond the periphery of the imperforate disk so as to turn downward the air as it passes through the throats produced between the impeller plates, the disk and the plate ring, and a case extending around the impellers and of gradually increasing diameters, and a suction inlet at the smaller end of the case through which air is drawn into the case and expands toward and is delivered from the larger end of the case.

3. A vacuum producing apparatus comprising spaced impellers of gradually increasing diameters, a case therefor extending around the impellers and also of gradually increasing diameters and in which are expansion chambers between the impellers, and said case having off-set portions adjacent to the edges of the impellers and corresponding in outline with the peripheries of the impellers, and partition rings or separators connected at their outer edges to the case and extending inwardly directly over the impeller devices.

4. A vacuum producing apparatus comprising spaced impellers of gradually increasing diameters, a case therefor extending around the impellers and also of gradually increasing diameters and in which are expansion chambers between the impellers, and said case having off-set portions adjacent to the edges of the impellers and corresponding in outline with the peripheries of the impellers, partition rings or separators connected at their outer edges to the case and extending inwardly directly over the impeller devices, and a curved annulus at the larger open end of the case secured to the case and forming a chamber beneath the larger impeller device.

5. A vacuum producing apparatus comprising series of revoluble devices or spaced impellers of gradually increasing diameters, a central shaft on which the said devices are mounted and each device comprising a hub upon the shaft, an imperforate disk secured thereto, series of impeller blades connected to the upper surface of said disk adjacent to and extending inward from the periphery of the disk and the impeller blades set at an inclination crossing radial lines, an over-head plate ring having its inner edge at the

inner ends of the impeller blades extending over the blades so as to produce throats between the blades, the disk and the ring, with the outer edge of the plate ring continued 5 beyond the periphery of the imperforate disk and downwardly curved and over-turned so as to produce a delivery wall, and a case also of gradually increasing diameter extending around the revoluble impeller devices and having off-set portions extending closely around and adjacent to the periphery of the revoluble impeller devices and said case also provided with partition rings or 10 separators coming above the revoluble impeller devices and assisting in establishing chambers of the case between said revoluble impeller devices.

6. A vacuum producing apparatus comprising series of revoluble devices or spaced 20 impellers of gradually increasing diameters, a central shaft on which the said devices are mounted and each device comprising a hub upon the shaft, an imperforate disk secured thereto, series of impeller blades connected to the upper surface of said disk adjacent to and extending inward from the periphery of the disk, and the impeller blades set at an inclination crossing radial lines, an over-head plate ring having its 30 inner edge at the inner ends of the impeller blades extending over the blades so as to produce throats between the blades, the disk and the ring, with the outer edge of the plate ring continued beyond the periphery of the imperforate disk and downwardly curved and over-turned so as to produce a delivery wall, and a case also of gradually increasing diameter extending around the revoluble impeller devices and having off-set portions agreeing substantially with the 35 curved peripheries of the said revoluble impeller devices and also partition rings or separators arranged parallel with and directly above the revoluble impeller devices 40 secured at their peripheries to the case and having their inner edges over-turned into the central portion of the rotary impeller devices.

7. A vacuum producing apparatus comprising series of revoluble devices or spaced 50 impellers of gradually increasing diameters, a central shaft on which the said devices are mounted and each device comprising a hub upon the shaft, an imperforate disk secured thereto, series of impeller blades connected to the upper surface of said disk adjacent to and extending inward from the periphery of the disk, and the impeller blades set at an inclination crossing radial lines, an over-head plate ring having its 60 inner edge at the inner ends of the impeller blades extending over the blades so as to produce throats between the blades, the disk and the ring, with the outer edge of the plate ring continued beyond the periphery 65

of the imperforate disk and downwardly curved and over-turned so as to produce a delivery wall, and a case also of gradually increasing diameter extending around the revoluble impeller devices and having off-set portions agreeing substantially with the 70 curved peripheries of the said revoluble impeller devices and also partition rings or separators arranged parallel with and directly above the revoluble impeller devices 75 secured at their peripheries to the case and having their inner edges over-turned into the central portion of the rotary impeller devices, and a curved annulus at the larger open end of the case secured within the 80 case, preferably contracting the exit opening of the case so as to establish a receiving chamber for the air at the larger end of the case.

8. A vacuum producing apparatus comprising with a case of gradually increasing 85 diameters, spaced impellers therein also of gradually increasing diameters and between which are expansion chambers, each impeller having a central air intake toward 90 the smaller part of the case and a peripheral discharge substantially at right angles to the plane of the impeller.

9. A vacuum producing apparatus comprising with a case of gradually increasing 95 diameters, spaced impellers therein also of gradually increasing diameters and between which are expansion chambers, each impeller having a central air intake toward 100 the smaller part of the case and a periphery curved in a downward and outward direction for a peripheral discharge substantially at right angles to the plane of the impeller.

10. A vacuum producing apparatus comprising with a case of gradually increasing 105 diameters, spaced impellers therein also of gradually increasing diameters and between which are expansion chambers, each impeller having a central air intake toward 110 the smaller part of the case and a peripheral discharge, and means protecting the gap at the intake margin, which means extends down into the central air intake to control the direction of the moving currents of air.

11. A vacuum producing apparatus comprising with a case of gradually increasing 115 diameters, spaced impellers therein also of gradually increasing diameters and between which are expansion chambers, each impeller having a central air intake toward 120 the smaller part of the case and a peripheral discharge, means protecting the gap at the intake margin, which means extends down into the central air intake to control the direction of the moving currents of air, and 125 a curved deflecting wall at the periphery of the spaced impellers having the function of a peripheral discharge substantially at right angles to the plane of the impeller simultaneously effecting a seal of the gap. 130

12. A vacuum producing apparatus comprising with a case of gradually increasing diameters, spaced impellers therein also of gradually increasing diameters and between 5 which are expansion chambers, and each of which impellers is provided with a series of conduits for fluid and the continuation of said conduits turned at the periphery of the impeller to a delivery opening which 10 faces the discharge.

13. A vacuum producing apparatus comprising a case having integral parts of gradually increasing diameters with curved shoulders between the parts, spaced impellers 15 within the case also of gradually increasing diameters, dividing the case up

into several expansion chambers, partition rings secured to the case at the shoulders thereof and directly above the impellers and assisting in dividing up the case into chambers, each impeller having a central air intake toward the smaller part of the case, and a peripheral wall curved downward and outward and coinciding with the curved shoulders of the case and effecting a downward discharge of the air. 20 25
